UNITED STATES PATENT OFFICE.

CHARLES S. LEDDELL, OF MENDHAM, NEW JERSEY.

STEERING DEVICE FOR BICYCLES.

SPECIFICATION forming part of Letters Patent No. 367,049, dated July 26, 1887.

Application filed September 30, 1886. Serial No. 214,931. (No model.)

To all whom it may concern:

Be it known that I, CHARLES S. LEDDELL, of Mendham, in the county of Morris and State of New Jersey, have invented a new and useful Improvement in Steering Devices for Bicycles, of which the following is a specification.

My steering devices are intended for that class of machines which are normally operated with the smaller wheel in advance, and in which the smaller wheel must therefore be turned to effect the steering of the machine.

The object of my invention is to provide a very simple steering device for machines of this class; and the invention consists in novel combinations of parts, which are hereinafter described, and referred to in the claims, and in which are included, as essential elements, an approximately upright shaft journaled in the frame at the side of the large driving-wheel, and having at the lower portion a crank connected with the steering-wheel shaft and a handle at the upper end of the rock-shaft, whereby it may be turned.

In carrying out my invention the machine will usually be provided with two approximately upright rock-shafts at opposite sides of the machine, and the handles at the upper ends of the rock-shafts may be connected, so as to cause them to move simultaneously in reverse directions. The connection between the lower ends of the rock-shafts and the steering-wheel shaft may be formed by rods extending from the cranks on the rock-shafts to laterally-projecting arms at opposite sides of the steering-wheel shaft; or, in lieu of rods, chains or other flexible connections might be employed; and, if desired, a single flexible connection might be carried around and secured to a wheel or hub upon the steering-wheel shaft and attached at the opposite ends to the cranks of the two rock-shafts.

The above-referred-to features of construction are included in my invention.

In the accompanying drawings, Figure 1 is a side elevation, Fig. 2 a plan, and Fig. 3 a rear view, of a machine embodying my invention. Fig. 4 is a side view of certain of the parts, which are shown in the previous figures upon a larger scale. Figs. 5 and 6 are respectively a side view and plan of parts of the machine, showing a modification of the invention. Figs. 7 and 8 are respectively an eleva-

tion and plan of the two rock-shafts and handles at the upper ends thereof, also including a transverse section of the backbone of the machine and a portion of the frame thereof, and in Fig. 7 portions of the length of the rock-shaft are broken away to reduce the size of the figure. Fig. 9 is a partly sectional elevation upon a larger scale, showing the upper end portions of the two rock-shafts with portions of their handles. Figs. 10 and 11 are respectively a plan and side view of parts illustrating a modified form of connection between the two rock-shaft handles. Figs. 12, 13, and 14 are respectively a rear elevation, a plan, and a side elevation showing another modified form of connection between the two steering-handles. Fig. 15 is a horizontal section illustrating another slight modification of the invention as regards the means employed to connect the steering-handles, and Fig. 16 is a plan or diagram showing a flexible connection as extending between the cranks at the lower ends of the steering-shafts and passing around a wheel or hub upon the steering-wheel shaft.

Similar letters of reference designate corresponding parts in all the figures.

I have in the drawings shown only such parts as are necessary to illustrate my invention, and the remaining parts necessary to form a complete machine may be of any suitable or ordinary character.

A B designate, respectively, the large driving-wheel and the smaller steering-wheel.

C designates the forked steering-wheel shaft.

D designates the backbone, curved to conform to the circumference of the wheel A.

E designates the main shaft or axle, on which is supported a lower frame portion, F, at each side of the wheel A.

G designates an upper frame portion, which receives the backbone D through it, and H designates tubular braces which extend from the upper frame portion, G, downward to the lower frame portion, F.

I designates braces or brace-rods, which extend from the lower frame portion, F, at each side of the machine forward to a collar, I', which surrounds the steering-wheel shaft C.

J designates two approximately vertical or upright rock-shafts, arranged one at each side of the machine, but having their lower portions, J', inclined inward relatively to the axes of the

main portions of the rock-shafts, so as to form cranks, from which rods J^2 extend forward and are connected with laterally-extending arms j upon opposite sides of the steering-wheel shaft 5 C. The construction of the cranks J' by inwardly-inclined portions of the rock-shafts J is important, because the cranks then conform to the converging profile of the main wheel A from its center downward, as shown best in 10 Fig. 3, and no unnecessary room is occupied. If the cranks were formed by lateral projections from their shafts in the ordinary way, the frame portions would have to be extended downward to the cranks, or else the cranks 15 would have to be formed upon the shafts J immediately below the present frame portions F, and in the latter case the cranks, if they extended inward from their shafts toward the wheel A, would, by reason of the thickness of 20 the wheel at the center, necessitate the placing of the rock-shafts J farther apart. In lieu of the rods J^2 , extending between the rock-shafts and the steering-wheel shaft, chains or analogous flexible connections might be substituted, 25 and in lieu of having arms upon the steering-wheel shaft, I may employ a single flexible connection, J^3 , attached at the ends to the two cranks J' , as shown in Fig. 16, and passed around a wheel or hub, C, on the steering-wheel shaft, the connection J^3 being secured 30 to the wheel or hub C' at c, all as shown in Fig. 16.

From the foregoing description it will be readily understood that by turning the rock-shafts J in opposite directions the steering of the machine will be effected, and if a single rock-shaft were employed at one side of the machine only the steering of the machine would be effected by turning this shaft in one 40 or other direction.

At the upper ends of the rock-shafts J are steering-handles or handle-arms J^4 , of which two are best represented in Figs. 7 and 8. Obviously, if these bent handles and the cranks 45 J' at the lower ends of the rock-shafts J were formed integral with the shafts, the latter could not be arranged within the tubular braces H of the machine, as they are shown arranged in Figs. 1, 2, 3, and 4, and I therefore 50 in such case make the handle-arms J^4 separable from the rock-shafts J , and secure them adjustably thereto. One means of securing them to the rock-shafts is illustrated in Fig. 9. The rock-shafts J , which may consist of tubes, 55 are shown in Fig. 9 as provided at their upper ends with conical screw-threads j' , to which are applied conical nuts j^2 , and the conically-threaded portions are split or slotted, in order to form from them elastic jaws, which are 60 clamped upon the handle portions J^4 , entering into them by tightening up the nuts j^2 .

The two handle-arms or steering-handles J^4 and their rock-shafts J may be connected in many different ways, so as to turn simultaneously in opposite directions. I have in Figs. 65 7, 8, and 9 shown the handle-arms as provided with laterally-extending arms k upon opposite

sides, and such arms k may be connected upon opposite sides of the rock-shafts J by chains k' . (Best shown in Figs. 8 and 9.) In order 70 to provide for taking up all slack motion, one end of each chain k' may be swiveled in the arm k , projecting from one handle J^4 , as shown at k^2 , and may be secured by a screw-threaded shank or stud, k^3 , in the arm k , projecting from 75 the other handle, J^4 . The connections k' may then both be maintained taut or under tension, so that the slightest turning of one handle J^4 and rock-shaft J will produce an equal but reverse turning movement of the other handle 80 and rock-shaft.

In some cases it may be desirable not to have the rock-shafts J extend through the tubular braces H, and in such case the rock-shafts may be supported at the upper end in a frame portion, G, and may be supported near the lower end in bearings K, which may be secured by set-screws d upon the forwardly-extending braces or brace rods I, as shown in Figs. 5 and 6.

In lieu of employing the system of connections between the handles J^4 which are shown in Figs. 7, 8, and 9, I may provide upon the upper ends of the rock-shafts J pinions e , which engage with the intermediate pinion, e' , pivoted on the upper frame portion, G, and as shown in Figs. 10 and 11. The handles will then move simultaneously and equally in reverse directions. In Figs. 12, 13, and 14 I have represented the two handles J^4 as comprised in a single bar, which is secured at the upper end of the shaft f , mounted in a bearing, h , formed upon the upper frame portion, G, and said shaft f is provided at its lower end with a pinion, f' , which engages the pinions e upon the upper end of the rock-shafts J . The turning movement of the shaft f and pinion f' will then produce a movement in reverse directions of the two pinions and the rock-shafts J , upon which they are mounted.

In lieu of pinions in the arrangement shown in Figs. 12, 13, and 14, I may employ smooth-surfaced wheels or hubs e^2 , as shown in Fig. 15, and connect them by a band or flexible connection, e^3 , secured to each of them and embracing all of them, as shown in Fig. 15. With this arrangement a like result will be secured.

The above-described connections for the handles at the top of the rock-shafts may be dispensed with when the crank ends of the rock-shafts are connected by rods with the steering-wheel shaft, because by said rods any turning movement of one rock-shaft will be communicated in reverse direction to the other 125 rock-shaft.

In Figs. 1, 2, and 3, I rely entirely on the rods and steering-wheel shaft C to connect the rock-shafts.

What I claim as my invention, and desire 130 to secure by Letters Patent, is—

1. The combination, with the steering-wheel shaft and with the upper and lower frame portions of a bicycle, of a tubular brace connect-

ing the upper and lower frame portions at the outer side of the driving wheel, an approximately upright rock-shaft extending through said tubular brace and provided at the lower 5 end with a crank connected with the steering-wheel shaft, and a handle at the upper end of said rock-shaft, whereby it may be turned, substantially as herein described.

2. The combination, with the steering-wheel shaft and with the upper and lower frame portions of a bicycle, of a tubular brace connecting the upper and lower frame portions, a rock-shaft extending through said brace and having below the brace an integral crank connected with the steering-wheel shaft, and a handle-arm detachably connected with the upper end of said rock-shaft above the brace, substantially as herein described.

3. The combination, with the steering-wheel shaft of a bicycle, of an approximately upright rock-shaft extending downward from the upper portion of the machine at the side of the driving-wheel, having its lower portion inclined downward relatively to its axis to 20 form a crank, which is connected with the steering-wheel shaft and the inclination of which conforms approximately to the converging profile of the wheel from its center outward to its circumference, and a handle at the

upper end of the rock-shaft, substantially as 30 herein described.

4. The combination, with the steering-wheel shaft of a bicycle, of approximately upright rock-shafts at opposite sides of the machine, having at the lower ends cranks which are 35 connected with the steering-wheel shaft, and handles at the upper ends of said rock-shafts connected with the rock-shafts and with each other, so as to move and cause the turning of the rock-shafts simultaneously in reverse directions, substantially as herein described.

5. The combination, with the steering-wheel shaft of a bicycle, of approximately upright rock-shafts at opposite sides of the machine, provided at the lower ends with cranks connected with the steering-wheel shaft and provided at the upper ends with handle-arms directly surmounting them, and connections between the handle-arms and rock-shafts whereby the handle-arms with their shafts are 45 caused to move simultaneously in reverse directions, and which are adjustable to take up lost motion between them, substantially as 50 herein described.
